UNITED STATES PATENT OFFICE.

LOUIS FRANKLIN STEVENS, OF NEW YORK, N. Y.

HOSE-THIMBLE FOR THE WALLS OF BUILDINGS.

SPECIFICATION forming part of Letters Patent No. 389,025, dated September 4, 1888.

Application filed April 14, 1888. Serial No. 270,638. (No model.)

To all whom it may concern:

Be it known that I, LOUIS FRANKLIN STEVENS, of the city, county, and State of New York, have invented a new and Improved Hose-Thimble for the Walls of Buildings, of which the following is a full, clear, and exact description.

The object of my invention is to provide a practical tube or thimble to be built into the walls of buildings and through which a hose-nozzle may be thrust for extinguishing fire; and to this end my invention consists of the construction, arrangement, and combination of parts, all as hereinafter described and claimed.

Reference is to be had to the accompanying drawings, forming a part of this specification, in which similar letters of reference indicate corresponding parts in all the figures.

Figure 1 is a sectional elevation illustrating a masonry wall having my invention built therein, and showing a hose-nozzle passed through the thimble. Fig. 2 is a front elevation of the wall and thimble, showing the thimble closed. Fig. 3 is a sectional elevation of the same, and Fig. 4 is an enlarged plan view of one of the locking-bolts.

A represents a tube or thimble, preferably of brass, cement, or cast-iron, and adapted to be built into a brick or other wall, B. Each end of the thimble A is provided with a hinged door, C, adapted to close the tube or thimble, and each door is provided with a spring-actuated locking-bolt, D, which is adapted to engage with a recess, i, in the thimble for holding the door closed. Each locking-bolt is held to slide in suitable keepers, a, and is formed with a projection, a', with which a key, b, passed through the key-hole b', may engage for disengaging the bolt from the recess i for opening the door, and each locking-bolt D is formed with a frame, D'. (Shown clearly in Fig. 4.) In the center of each door C is secured a pin, d, on which is placed loosely a

plate, E, which is adapted to slide upon said pin. The inner surface of each plate E is formed with a cone, E', which passes through the frame D' of the locking-bolt D, so that when the plate is thrust forward on the pin d the cone will act to withdraw the locking-bolt, and thus unlock the door.

The thimble is, by preference, depressed in the center, each end being slightly flaring to facilitate the insertion of the nozzle N, and also to adapt it to be secured more firmly in the wall. When both of the doors C are closed, all passage of air through the thimble is prevented, and in case of fire in the building the outside door may be opened by a key and the nozzle thrust into the thimble, whereupon the end of the nozzle will strike the plate E and force it forward on the pin d, causing the cone E' to withdraw the locking-bolt, and thus automatically open the inner door. By this means the necessity of breaking holes in walls to extinguish fire in the building may be wholly obviated.

Having thus described my invention, what I claim as new, and desire to secure by Letters Patent, is—

1. The thimble A, having hinged doors C, provided with locking-bolts formed with frames D', in combination with the studs d, and plates E, placed loosely thereon and formed with cones E', substantially as described.

2. The casing A, adapted to be built in a wall and provided at the ends with a hinged door, C, in combination with a locking-bolt in the same plane with the door, and a movable plate, E, adapted to be pressed by the hose-nozzle for withdrawing the sliding locking-bolt, substantially as described.

LOUIS FRANKLIN STEVENS.
